UNITED STATES PATENT OFFICE.

EDWIN BURHORN, OF HOBOKEN, NEW JERSEY.

SUBAQUEOUS ROCK-BREAKER.

No. 892,645.

Specification of Letters Patent.

Patented July 7, 1908.

Application filed November 27, 1907. Serial No. 404,161.

To all whom it may concern:

Be it known that I, EDWIN BURHORN, a citizen of the United States of America, residing in the city of Hoboken, county of Hudson, and State of New Jersey, have invented a certain new and useful Improvement in Subaqueous Rock-Breakers, of which the following is a true and exact description, reference being had to the accompanying drawings, which form a part thereof.

My improvement relates to that class of sub-aqueous rock-breakers used in river and harbor improvements, employing a reciprocating weight or hammer to drive a wedge or conical shaped point or chisel into the rock or ledge in order to shatter and disintegrate the same, and render its removal possible by dredging machines. This type of rock-breaking apparatus has been rendered much more efficient, especially in deep water, by the addition of a caisson or tube for excluding the water from contact with the reciprocating parts, and so eliminating the water resistance that would be otherwise encountered; and it is to this improved type that my improvement particularly relates. When operating these machines in deep water the striking parts are necessarily submerged to great depths, and hence beyond the direct observation of those operating the apparatus, and consequently if breakage of the machine occurs at or adjacent to these striking parts, which necessarily is a common occurrence, such breakage though it may be trivial at first, cannot be detected by the operator until serious wreck or damage ensues. Foreign matter, such as sand, earth and small stones, may enter the spaces adjacent to the striking parts through the air vents, P, Figures 2 and 3, and cause trouble by clogging or otherwise impeding the proper action of the parts.

The objects of my invention are to provide means whereby the presence of any foreign matter, adjacent to the striking parts, or the breakage or disarrangement of the parts themselves, may be immediately detected by the operator, and thus enable him to cease operation, examine, repair, replace, or remove, any broken, or disarranged parts, or foreign matter that might cause trouble, should further rock-breaking proceed.

Reference now being had to the drawings

in which my invention is illustrated, Fig. 1. shows a vessel floating at the water line W—W and equipped with rock-breaking apparatus of the improved type above mentioned. It shows the general arrangement of my safety device or detector. Fig. 2. shows the lower end of the tube or caisson, 60 and the hammer; also the chisel and chisel head or striking face, and mouthpiece supporting same; with one form of my safety device applied to same. Fig. 3. illustrates the same arrangement of parts, with another 65 form of safety device. Fig. 4. is a plan view of Fig. 2. with the hammer and tube removed. Fig. 5. is a plan of Fig. 3., under the same conditions. Figs. 6 and 7 show another application of my device, to the same 70 arrangement of parts, in sectional elevation and plan, and Figs. 8 and 9 illustrates in sectional elevation and plan, another form of my device.

Similar letters, refer to similar parts. 75
In Fig. 1. D is a vessel floating at the water line W—W, and carrying a boiler F., engine E. and air compressor L, for operating the rock-breaking machinery and keeping the tube or caisson free from water, as understood by those familiar with the art. Mounted on the vessel is the frame X, for carrying the hoisting tackle G and I, and provided with guides Q, for maintaining the caisson or tube A, upright when resting on the rock R. 80 The tube A, extends through a well O, in the vessel's hull, indicated in dotted lines and contains a hammer H, mouthpiece B, and chisel C. This arrangement and combination of parts, has formed the subject matter 85 of former patents and applications and is familiar to those acquainted with the art; and forms no part of the invention claimed in this specification. It is introduced solely to illustrate the relation and function of the 90 subject matter claimed as novel.

Referring now to Fig. 2., it will be seen the hammer H and the chisel-head C¹ are in contact, as in the striking position. Completely surrounding these striking parts, is the wall 100 of the mouthpiece B, thus leaving between them an annular space S. It is obvious, that if for instance, the chisel-head C¹ should crack, and a fragment should wedge in this annular space S, successive blows of the hammer H, might drive it down farther and suffi-

ciently to fracture the wall of the mouth-piece B, and so produce a serious and expensive wreck; whereas if knowledge of the presence of this fragment in the annular space, could be immediately conveyed to the operator, he could cease operations, remove the mouthpiece, replace the broken hammer head and proceed again, without any disastrous consequences. In general it may be said, that if this annular space surrounding the two striking parts, is clear, the operation of the machine is normal and safe, the presence of anything in this space indicating that something is wrong.

15 In Fig. 2., m^1 is an insulated electric wire, passing to the inside of the mouthpiece B, through the hole B¹. The insulation consists of a rubber tube m^5 , through which is drawn the bare wire m^1 . After entering the mouthpiece, this wire is looped back and forth in a vertical direction, completing the full circle of the interior wall of the mouthpiece, this is shown more clearly by reference to Fig. 4. The end is secured at a higher level than the loops, and the bare wire allowed to protrude from the insulation as at m^6 . It will now be obvious that if any fragment enters the annular space S, it will rupture the rubber tube and expose the bare wire to contact with any 30 adjacent conductor.

Returning now to Fig. 1., which shows the general arrangement of my preferred device, given in detail on Figs. 2 and 4, m^3 is a battery, and m^4 in circuit with same, an alarm fixture such as a bell or buzzer. The circuit is composed of the wires m^1 and m^2 of which m^1 connects with the safety device m as above described; and m^2 is connected to the metallic tube A, which in turn touches the 40 metallic hammer H, and mouthpiece B, which in turn touches the metallic chisel C. It will thus be seen that the tube A, and all touching parts are electrified, and that a contact with any part of the wire m^1 , will complete the circuit and sound the alarm. This 45 circuit is of course completed if the rubber tube m^5 is ruptured, or the air pressure in the caisson is lessened sufficiently to let the water rise to the level of the bare end m^6 . This 50 latter method of making contact is useful to test the device when desired.

In Fig. 3, the underlying idea is the same though the method is different. The annular space S, is filled by the annular air tight 55 tank N. Connected with this tank is the tube n^1 , leading to the vessel above, through which a constant air pressure is maintained, greater than the maximum hydrostatic head due to depth of submergence. Connected to 60 this tube is a gage, visible to the operator (not shown). It is now obvious if a fragment of one of the striking parts enters the annular space S, it will puncture the sides of the annular tank, allow the air to escape, the

loss of pressure will be registered upon the 65 gage, and so give warning to the operator.

Figs. 6 and 7, show another application, differing from those already described, in that nothing is ruptured or broken in order to produce the alarm. Electricity is the signaling medium used. T, is a plain metallic cylinder insulated from the mouthpiece B, by the insulating blocks t. The circuit is similar to that used in the device of Figs. 2 and 4, the down wire in this case being t^1 . It 70 is obvious if any break occurs, and a fragment touches the cylinder T, contact will be made, and the circuit completed.

Figs. 8 and 9, in plan and sectional elevation, show another device, in which the condition of the striking parts can be observed by the eye. U², is a tube parallel with the caisson, and extending from above the water line W-W, to the reflector box U⁷, from thence at right angles to U², extends a tube 85 U¹ passing to the interior of the mouthpiece B, these connections being all made water tight. Inside the reflector box U⁷ is a mirror U³ at 45 degrees to the axes of the respective tubes U² and U¹. Within the mouthpiece B, are arranged a series of electric lamps U⁴, fed by the wires U⁵, which extend from the vessel above. It is perfectly clear, that upon illuminating the interior of the mouthpiece B, with the lamps U⁴, and applying the eye of the operator U⁶ to the open end of the tube U², a perfect view of the condition of the striking parts may be obtained. 95

The fundamental idea may be carried out in many ways, air could be used in the tube 100 of the device shown in Figs. 2 and 4 instead of electricity; or electric contacts could be fitted in the annular tank of the device shown in Figs. 3 and 5; the pressure of liquids might be used in place of air or electricity, and lastly, purely mechanical combinations of levers and connecting cords or links, might be employed; for these reasons I do not limit the scope of my claims to the specific constructions shown. 110

Having now described my invention, what I claim as new and desire to secure by Letters Patent is;

1. In a sub-aqueous rock-breaker, having submerged striking parts; means whereby 115 the operator may detect the presence of foreign matter adjacent to said parts, or any breakage or disarrangement of said parts themselves.

2. In a sub-aqueous rock-breaker, means 120 whereby the presence of foreign matter and broken parts in the annular space adjacent to the striking parts, may be detected by the operator.

3. In a sub-aqueous rock-breaker, a device 125 in the annular space adjacent to the striking parts, that will be affected by the presence of foreign matter and broken parts in such

space; in combination with means for indicating or registering such effect at any selected point.

4. In a sub-aqueous rock-breaker a continuous tube occupying a portion of the annular space, adjacent to the striking parts; and means whereby the rupturing of said tube may be registered at a selected point.

In testimony whereof I have signed my name to this specification, in the presence of 10 two-subscribing witnesses, on the 21st day of November 1907.

EDWIN BURHORN.

In presence of—

LOUIS A. PHILLIPS,

A. BOULOGNE.
